UNITED STATES PATENT OFFICE.

ALBERT A. FRANKL, OF NEW YORK, N. Y.

DESIGN FOR A TRIMMING OR FRINGE.

SPECIFICATION forming part of Design No. 21,678, dated July 5, 1892.

Application filed May 27, 1892. Serial No. 434,675. Term of patent 3½ years.

To all whom it may concern:

Be it known that I, ALBERT A. FRANKL, a citizen of the United States, residing in the city, county, and State of New York, have invented and produced a new and original Design for a Trimming or Fringe, of which the following is a specification.

This invention relates to a design for a trimming or fringe. It consists of a heading, 10 pendent bands suspended from said heading, said bands being of different lengths, and balls at the ends of the bands.

The nature of my design is fully shown in the accompanying drawing.

15 A in the drawing represents a heading. Bare pendent bands that are suspended from said heading, the rear row of bands being made

longer than the front row, both rows of pendent bands being provided with ball-shaped terminals C, that are covered with a fabric 20 corresponding to that of the heading.

Having thus described my invention, what I claim as new, and desire to secure by Letters Patent, is—

The design for a trimming or fringe, substantially as shown and described.

In testimony that I claim the foregoing as my invention I have signed my name in presence of two subscribing witnesses.

ALBERT A. FRANKL.

Witnesses:

PAUL GOEPEL,
CHARLES SCHROEDER.
